UNITED STATES PATENT OFFICE.

MAURICE M. GLASSER, OF CHARLESTON, SOUTH CAROLINA.

FAN.

Application filed March 15, 1923. Serial No. 625,348.

To all whom it may concern:

Be it known that I, MAURICE M. GLASSER, a citizen of the United States, and a resident of Charleston, in the county of Charleston and State of South Carolina, have invented certain new and useful Improvements in Fans, of which the following is a full, clear, and exact description, reference being had to the accompanying drawings, forming a part of this specification.

This invention relates particularly to electric ceiling fans although it is applicable to other types of fans as will be apparent from the ensuing description.

15 In my prior Patent No. 1,354,098, granted September 28, 1920, there is disclosed and claimed a ceiling fan whose rotor and blades are rotated about a vertical axis and oscillated on a horizontal axis for the purpose of 20 causing the blast of air from the fan blades to move through an arc and changing the direction of that arc. The mechanism in that patent for accomplishing said movements of the rotor and blades, however, requires that the rotation of the rotor and 25 blades be dependent on the oscillation of said rotor and blades with the result that if the oscillation of the rotor and blades is not constant, the rotation of the rotor and 30 blades will be intermittent.

Therefore, an object of the present invention, stated broadly, is to provide a fan whose rotor and blades are oscillated by suitable mechanism on an axis in one plane 35 to direct the blast of air in an arc and whose rotor and blades are rotated by an entirely independently operable mechanism on a different axis to change the direction of said arc. Whether or not the rotation of the 40 rotor as well as the oscillation of the same, is constant or intermittent, is immaterial so far as the present invention is concerned for with the two mechanisms arranged independently of each other, either or both of 45 these movements may be constant or intermittent, as desired. Preferably, however, the rotor and blades are moved continuously, as illustrated in the accompanying drawings.

50 In the drawings—

Figure 1 is a front view of a fan embodying the present improvements, portions being broken away to facilitate illustration;

55 Fig. 2 is a view taken at right angles to Fig. 1;

Fig. 3 is a detail view of the mechanism for securing the independent rotation of the rotor and blades.

While the present invention is applicable to other types of fans it has, in the present 60 instance, been illustrated as applied to a fan like that disclosed in my prior patent before referred to.

In this type of fan the fan motor proper is enclosed within a casing 10 pivotally 65 mounted on a horizontal axis in a yoke 11 journaled on a vertical stationary hollow post 12 which has a base 13 that may be secured to the ceiling in any desired manner. The lower end of the fan motor shaft 14 70 carrying the fan blades 15 protrudes below the casing 10 but it will be understood that this arrangement may be reversed—that is, the blades 15 may be mounted on the casing and said casing rotated, as in some 75 of the well known types of fans. Current is supplied to the fan motor in any suitable way as by conductors 16, 17 connected to brushes 18, 19 which are mounted on a rotating sleeve 20 on post 12 and which contact with rings 21, 22 on said post, said rings being supplied with current by wires 23 leading thereto from a source of supply through the hollow post and through openings 24 in said post.

85 For oscillating the casing, motor and blades on the horizontal axis of the casing, the upper end of the fan motor shaft 14 extends up into a dome 25 on the casing and is provided at its upper end with a worm 26 90 which meshes with a worm gear 27 mounted on one end of a horizontal shaft 28 journaled in bearings formed on the casing. The opposite end of the shaft 28 has a disk 29 mounted thereon and said disk is connected 95 by a link 30 to a similar disk 31 mounted on one of the journal pins 32 of the casing. The link 30 is eccentrically connected to each of said disks 29, 31 and upon rotation of said disks by the fan motor shaft the fan 100 motor casing and parts carried thereby will be oscillated on the horizontal axis of said casing, as will be understood. A more detailed description of these parts, and of their operation, if found desirable, may be 105 had from my prior patent.

The casing 10, fan motor and blades 15 being supported in yoke 11, the preferred arrangement for rotating the casing, blades, etc., consists in providing means for rotating 110

said yoke on the post 12. While these means and its rotor, a revolving support for the for rotating the yoke may assume any of various forms as far as the present invention in its broadest aspect, is concerned, so long as they are operable independently of the means for oscillating the casing, they preferably consist of a motor 33 mounted adjacent the upper end of post 12, rotary motion of the motor shaft 34 of this motor being transmitted to the yoke 11 by a worm 35 on said shaft meshing with a worm gear 36 on a shaft 37 and a small gear 38 on said shaft 37 meshing with an internal ring gear 39 mounted on the yoke. Current is supplied to motor 33 by wires 40. All of said gears being perfect, as distinguished from one of them (say gear 38), being mutilated, a smooth, continuous rotary movement will be imparted to the casing, etc., regardless of the continuity, or lack of continuity, of the oscillatory motion given those parts.

In addition to securing a smooth, continuous rotation of the casing, etc., the independent rotation of said parts reduces the jar upon the main motor and reduces the strain on that motor.

What is claimed is:

1. In a fan, the combination of a motor and its rotor, a series of blades carried by the rotor, means for oscillating the rotor and blades, and means for revolving said rotor and blades, said rotor oscillating and revolving means being operable independently of one another.

2. In a fan, the combination of a motor and its rotor, a series of blades carried by the rotor, means for oscillating the rotor and blades, and means for continuously revolving said rotor and blades, said rotor oscillating means being operable independently of the means for revolving the rotor and blades.

3. In a fan, the combination of a motor

and its rotor, a support therefor, a series of blades carried by the rotor, means for oscillating the rotor and blades, an auxiliary motor, and connections between said auxiliary motor and said support for revolving said support.

4. In a fan, the combination of a motor and its rotor, a support therefor, a series of blades carried by the rotor, means for oscillating the rotor and blades, an auxiliary motor, and connections between said auxiliary motor and said support for revolving said rotor and blades.

5. In a fan, the combination of a fixed post, a yoke journaled on the post, a motor and rotor supported in the yoke, means operable by the motor for oscillating the rotor on its support, blades carried by the rotor, and means supported by the post for revolving said yoke, said revolving means being operable independently of said rotor oscillating means.

6. In a fan, the combination of a fixed post, a yoke journaled on post, a motor and its rotor supported in the yoke, means operable by said motor for oscillating said rotor on its support, blades carried by the rotor, and independently operable motor on said post and connections between said motor on the post and said yoke for revolving the latter.

7. In a fan, the combination of a post, a yoke journaled on the post, a motor and its rotor supported in the yoke, means operable by said motor for oscillating the rotor, blades carried by the rotor, and means for revolving said yoke, said revolving means comprising an independently operable motor and rotor, a worm on said rotor, a ring gear on said yoke, a shaft, and gears on said shaft meshing with said worm and ring gear.

MAURICE M. GLASSER.
